(57) **CLAIM**

The ornamental design for a corona tip for an antenna, as shown.

DESCRIPTION

FIG. 1 is an elevational view of a corona tip for an antenna according to the present design;

FIG. 2 is a top plan view of a corona tip for an antenna according to the present design; and,

FIG. 3 is a bottom plan view of a corona tip for an antenna according to the present design.

The broken lines in the Figures are for illustrative purposes only and form no part of the claimed design.
